UNITED STATES PATENT OFFICE

154,604

DESIGN FOR AN ADVERTISING CLOCK

Henry S. Greenstone, Los Angeles, Calif.

Application August 27, 1948, Serial No. 148,343

Term of patent 3½ years

(Cl. D42—7)

To all whom it may concern:

Be it known that I, Henry S. Greenstone, a citizen of the United States, residing in the city and county of Los Angeles and State of California, have invented a new, original, and ornamental Design for an Advertising Clock, of which the following is a specification, reference being had to the accompanying drawing, forming part thereof.

Fig. 1 is a face view of an advertising clock, showing my new design.

Fig. 2 is a side elevation thereof.

The essential features of my design for an advertising clock are shown in full lines.

I claim:

The ornamental design for an advertising clock, as shown and described.

HENRY S. GREENSTONE.
